UNITED STATES PATENT OFFICE.

THOMAS S. KEMBLE, OF BUFFALO, NEW YORK, ASSIGNOR TO CURTISS AEROPLANE AND MOTOR CORPORATION, A CORPORATION OF NEW YORK.

EXHAUST-MUFFLER.

1,357,992.

Specification of Letters Patent. Patented Nov. 9, 1920.

Application filed November 22, 1916. Serial No. 132,824.

To all whom it may concern:

Be it known that I, THOMAS S. KEMBLE, a citizen of the United States, residing at Buffalo, in the county of Erie and State of New York, have invented certain new and useful Improvements in Exhaust-Mufflers, of which the following is a specification.

My invention relates in general to internal combustion engines and more particularly to that class of engines which are used for aeronautical work. It has for its object the muffling of the exhaust from the motor and accomplishes silent operation with less loss of power than usually attends the usage of other types of silencers or mufflers.

Essentially, my invention consists of an attenuated cone for the outlet end of the exhaust piping or manifold which carries throughout its entire length a slot, opening or aperture of certain fixed and definite dimensions. Through this slot the exhaust gases are dissipated in such manner that the usual explosion of the exhaust is rendered silent by reason of the relation of the dimensions of the slot to the piston displacement per cylinder and the firing period of the motor.

In order to eliminate the back pressure due to an attenuated manifold I construct the manifold so that its outlet area is considerably greater than the area of any cylinder exhaust port. The gases therefore are free to expand throughout their passage from the motor to the muffler proper at which point they are discharged through the slot in the side of the cone structure. As the gases are gradually discharged, a smaller sectional area is required for their proper passage, which diminishing sectional area is provided by the conical shape of the muffler.

My invention is here illustrated in connection with an eight cylinder motor of the V-type but it is equally adaptable to one or any multiplicity of cylinders in any of several arrangements.

Of the drawings:

Figure 1 is an elevation showing my muffler assembled to an aeroplane and motor;

Fig. 2 is a rear elevation in which the muffler is shown with conduits leading to the exhaust manifolds of the cylinders of each bank in a V-type motor;

Fig. 3 is a longitudinal section through the muffler;

Fig. 4 is a lateral section through the muffler;

Fig. 5 is a plan of an exhaust manifold;

Fig. 6 is an elevation of an exhaust manifold;

Fig. 7 shows the muffler and manifold assembled with an expanding conduit.

In Fig. 1 the muffler wholly designated as 10 is suspended from the fuselage of the aeroplane 11 by means of the clamps or clips 12. Leading from the manifold 13 to the muffler 10 is a pipe or conduit 14 which preferably has a constantly increasing diameter throughout its length from the manifold 13 to the muffler 10, in order to afford a free and unimpeded passage for the exhaust gases. In order to further expedite the flow of gases I also construct the manifold 13 so that its extreme outlet area is greater than that of any exhaust port. This is apparent from Fig. 5 in which 15 are the expanding conduits leading from the respective cylinders and 16 is the point of attachment of the conduit 14.

The muffler proper is in the nature of an extension of the manifold, and has a longitudinal slot or opening 17. The width of this slot I make extremely small compared to its length and the length is proportioned so that the total area of the slot will bear a proper relation to the firing period. The slot 17 is formed by flanging outwardly portions of the thin metal composing the walls of the conical muffler. These flanges 18 are held apart by the spacers or washers 19 (Fig. 3). The bolts as 20 penetrate the flanges 18 and the washers 19 and maintain the slot 17 at a practically constant width throughout its length. The distance between the washers along the length of the slot is such that the necessary rigidity will be given to the slot construction.

Although in other types of mufflers and silencers a large percentage of power is always destroyed, due to back pressure, my invention has no such drawback since the construction of the silencer and the manifold is such that at all points along the path of the exhaust gas egress a constantly increasing sectional area is afforded. This construction also reduces to a minimum eddies which are largely responsible for pipe-fric-

tion and back-pressures which are resultant therefrom. In its preferred embodiment I use my muffler and manifold in connection with an expanding conduit as shown in Fig. 7. However, the conduit 14 may be of uniform diameter throughout its entire length as in Fig. 1.

Although I have, for purposes of clarity, disclosed my invention as comprising certain specific constructional details, I do not consider it to be limited thereby, as it may consist of several embodiments without in any way departing from the spirit of the invention.

15 5 What is claimed is:

1. In combination with an internal combustion engine, exhaust manifolds of constantly expanding sectional area from their inlets to their outlet, and a conical muffler, 20 said muffler being provided with a narrow outlet slot or aperture extending substantially throughout its length.

2. In combination with an internal combustion engine, expanding exhaust manifolds, a conical muffler slotted substantially throughout its length, the slot in said muffler serving as a direct outlet for the gases from the conical chamber to the atmosphere, and a conduit of expanding sectional area from 30 its inlet to its outlet arranged to connect at its small and large extremities respectively with said manifold and said muffler.

3. In combination with an aeronautical internal combustion engine, a conical longitudinally slotted muffler, the slot in said muffler serving as a direct outlet for the gases from the muffler into the atmosphere, expanding exhaust manifolds and an expanding conduit to connect said manifolds to said muffler.

4. In combination with a multicylinder internal combustion engine, expanding exhaust manifolds, a conical longitudinally slotted muffler, the slot in said muffler serving as a direct passage for the gases from the conical chamber to the atmosphere and an expanding conduit leading from said manifolds to said muffler.

5. A muffler for an internal combustion engine comprising an elongated conduit gradually decreasing in cross-section from the forward to the rearward end, said conduit being apertured throughout its length to provide for direct passage of the gases from the restricted chamber of diminishing cross section to the atmosphere.

6. A muffler for an internal combustion engine comprising an elongated and attenuated cone which is apertured substantially from its base to its apex, the apertures leading directly from the restricted conical chamber to the atmosphere, whereby the gases are free and entirely unimpeded after emergence from the conical restricted chamber.

7. In an internal combustion engine, a muffler comprising a conical conduit having a series of marginally flanged holes or apertures extending substantially from the base of said cone to the apex thereof, said apertures leading directly from the restricted chamber of the conical conduit to the atmosphere. 70

8. A muffler for an internal combustion engine comprising an attenuated cone apertured substantially from its base to its apex, the apertures leading directly from the restricted conical chamber of the muffler to the atmosphere whereby the gases are free and entirely unimpeded after emergence from 80 the conical restricted chamber. 75

9. In combination with a multi-cylinder internal combustion engine, expanding exhaust manifolds and a longitudinally slotted muffler comprising an attenuated cone, said cone having its base attached to said manifolds and having its slot emerge directly into the atmosphere. 85

10. A muffler for an internal combustion engine comprising an elongated and attenuated conical conduit, said conical conduit having small lateral openings extending throughout its length for the purpose set forth, said openings leading directly from the conical chamber of the conduit to the 95 atmosphere. 90

11. A muffler for an internal combustion engine, comprising an elongated and attenuated cone, said cone having a narrow slot extending substantially throughout its 100 length for the purpose set forth, said slot opening directly into the atmosphere.

12. A muffler for an internal combustion engine, comprising a conically shaped conduit of thin metal, having a pair of flanges 105 formed thereon longitudinally of its length, said flanges inclosing a narrow slot extending throughout the elongated cone and said slot opening directly into the atmosphere for the purpose set forth. 110

13. A muffler for an internal combustion engine, comprising a conical shaped conduit of thin metal, having a pair of flanges formed thereon and extending longitudinally thereof, said flanges forming a longitudinal outlet slot in said muffler and being maintained in a spaced relation by spacers positioned at intervals throughout their length. 115

14. A muffler for internal combustion engines comprising a casing having a chamber of gradually decreasing cross sectional area from the foremost to the rearmost end and a distributed opening from one end of the restricted chamber to the other providing for 125 the direct emergence of the exhaust gases from the restricted chamber freely and unimpeded into the atmosphere. 120

In testimony whereof I affix my signature,
THOMAS S. KEMBLE.
